UNITED STATES PATENT OFFICE.

HENRY C. COFFMAN AND BENJAMIN F. VAN HORNE, OF GARY, INDIANA.

PHOTOGRAPHIC-PRINTING APPARATUS.

1,114,116.

Specification of Letters Patent.

Patented Oct. 20, 1914.

Application filed September 12, 1913. Serial No. 789,579.

To all whom it may concern:

Be it known that we, HENRY C. COFFMAN and BENJAMIN F. VAN HORNE, citizens of the United States, residing at Gary, in the county of Lake, State of Indiana, have invented certain new and useful Improvements in Photographic-Printing Apparatus; and we do hereby declare the following to be a full, clear, and exact description of the invention, such as will enable others skilled in the art to which it appertains to make and use the same.

This invention relates to photographic printing apparatus and particularly to that type in which an artificial light is employed to effect the printing.

The object of the invention resides in the provision of an apparatus of the character named in which the artificial lights are controlled automatically by opening and closing the hinged printing frame back, said lights being turned on when the negative and sensitized paper have been secured under the back and extinguished when the back is moved to open position to permit of the removal of the exposed paper.

A further object of the invention resides in the provision of an apparatus of the character referred to which includes means for elevating one end of the negative mechanically to permit of the convenient manual removal of the negative from the frame.

A still further object of the invention resides in the provision of means whereby the printing lights may be turned on without closing the back of the printing frame so as to allow the density of the negative to be inspected previous to the operation of printing, such inspection enabling the operator to determine the period of time the paper should be exposed to the artificial lights to effect the proper printing.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a plan view of the apparatus with the hinged back of the printing frame disposed in securing relation to a negative.

Fig. 2 a section on the line 2—2 of Fig. 1 with the hinged back of the printing frame partly open. Fig. 3 a plan view of the apparatus with the top and false bottom thereof removed. Fig. 4 a bottom view of the top of the apparatus with the printing frame disposed therein. Fig. 5 a section on the line 5—5 of Fig. 4. Fig. 6 a transverse section through the apparatus. Fig. 7 a section on the line 7—7 of Fig. 3. Fig. 8 a section on the line 8—8 of Fig. 4. Fig. 9, a section on the line 9—9 of Fig. 4, and Fig. 10 a detail perspective view of the gear element of the negative lifting device.

Referring to the drawings, the apparatus is shown as comprising a box or casing A which includes side members 15 and 16, a front member 17, a rear member 18, a bottom 19, a false bottom 20 and a removable top 21. The rear member 18 is provided centrally adjacent the bottom 19 with an opening 22 and mounted on the inner face of the rear member 18 at each side of the opening 22 are blocks 23 which support a strip of insulation 24 and this strip in turn carries electrical contacts 25 and 26 which project into the opening 22. This opening 22 is adapted to be closed by a door 27 suitably hinged to the outer side of the rear member 18. Mounted upon the bottom 19 at each corner of the casing is a block 28 and these blocks serve to support the false bottom 20 in spaced relation to the bottom 19. Adapted to be detachably engaged with the electrical contacts 25 and 26 when the door 27 is in open position is an electrical connection 29 which has secured thereto wires 30 and 31 leading from a suitable electrical source. Leading from the contact 25 is a wire 32 which is connected to a pivoted knife arm 33 mounted upon the inner side of the side member 15. Leading from the contact 26 is a wire 34 which is connected to a pivoted knife arm 35 mounted upon the inner side of the side member 15 in spaced relation to the arm 33 and for movement in a plane parallel to the plane of movement of said arm 33. Connected in multiple between the wires 32 and 34 is a plurality of electric lamp sockets 36. These sockets are mounted upon the bottom 19 and project respectively through openings 37 in the false bottom 20. Each of the sockets 36 carries a lamp 38 the globe of which is of any desired color, it being preferred however to use a lamp with a red globe in the socket

nearest the rear member 18 and lamps with clear globes in the remaining sockets.

Depending from the top 21 is a knife contact 39 which receives the knife arm 33. This top 21 is provided with an opening 40 for the reception of a printing frame B. Carried by the top 21 and extending into the opening 40 is a knife contact 41 which receives the knife arm 35. Mounted in the rear end of the top 21 are spaced conducting screws 42 and 43. The screws project slightly into the printing frame seat at their forward ends and said forward ends are provided respectively with recesses 44. The screw 42 is connected at its inner end to the knife contact 39 by means of a wire 45, while the inner end of the screw 43 is connected to the knife contact 41 by a wire 46.

The printing frame B includes the usual side members 47 and 48, rear member 49 and front member 50, said members being provided along their inner edge with a ledge 51 for supporting a negative. Hinged to the rear member 49 is the usual printing frame back which includes an inner member 52 and an outer member 53, the latter being hingedly connected to the free edge of the inner member 52. Mounted in the rear member 49 of the printing frame are spaced screw conductors 54 the inner ends of which engage in the recesses 44 of the conducting screws 42 and 43 respectively. The outer ends of these conducting screws 54 project slightly over the ledge 51 and are adapted to be engaged by the inner end of respective conducting members 55 mounted in the section 52 of the hinged back when said back is in closed position. The outer end of the conducting members 55 project slightly beyond the free edge of the section 52 and are adapted to be connected by a contact plate 56 mounted on the inner edge of the section 53 of the hinged back, such connection of the contact members 55 by the contact plate 56 occurring when the hinged top is in closed position as will be obvious. By this construction it will be obvious that when the hinged back of the printing frame is in partly open and open position the circuit through the lamps carried by the sockets 36 will be broken and that as soon as the hinged back of the printing frame B is moved to closed position the circuit through said lamps will be closed so as to provide the necessary light to effect the printing of the picture. The period of exposure in the printing operation is determined by the operator and when a sufficient period has elapsed the hinged back of the printing frame is moved to open position and the lights carried by the sockets 36 extinguished.

It is often desirable to turn on the lights carried by the sockets 36 without closing the hinged back of the printing frame for the purpose of allowing the density of a

negative to be inspected. In order to accomplish this result there is mounted on the inner side of the side member 15 a U-shaped member 57 disposed in embracing relation to the knife arms 33 and 35. The arms of the U-shaped member 57 are provided respectively with recesses 58 in which are slidably mounted the ends of a bar 59. This bar 59 is provided with a stem 60 which is slidable through an opening 61 in the side member 15. The bar 59 is normally held out of engagement with the knife arms 33 and 35 by means of a spring 62 which encircles the stem 60 and has one end connected to the member 57 and its other end to the bar 59. The outer end of the stem 60 has mounted thereon a push button 63 disposed on the outer side of the side member 15. By this construction it will be apparent that when the push button 63 is operated to move the stem 60 inwardly of the side member 15 the bar 59 will be brought into engagement with the knife arms 33 and 35 and in this manner the circuit through the lamp sockets 36 will be closed and the lamps carried by said sockets illuminated. As soon as pressure is relieved from the push button 63 the spring 62 will shift the bar 59 out of engagement with the knife arms 33 and 35. In this manner the lights of the apparatus may be illuminated for the purpose of inspecting the density of a negative independent of the closing of the hinged back of the printing frame B.

Mounted on the under side of the front member 50 of a printing frame is an angle member 64 which includes a depending arm 65 the lower end of which terminates in an angular portion 66 provided with a perforation 67. This arm 65 is further provided with a slot 72' for a purpose that will presently appear. Slidable in the perforation 67 is a plunger 69 provided on the side thereof adjacent the arm 65 with a notch 71'. The plunger 69 is normally held in its uppermost position by a spring 71 and the upper end of said plunger terminates in an angular portion 70 which extends over the ledge 51. Depending from the plate 64 parallel to the arm 65 is a bracket 70' upon which is pivoted a sear 72 working through the slot 72' and adapted to engage the notch 71' to hold the plunger 69 in its lowermost position against the influence of the spring 71. Depending from the plate 64 is a bracket 73 on which is pivoted a two armed lever 74. One end of this lever 74 extends under the end of the sear 72 remote from the arm 65 so that when the opposite end of said sear is depressed the sear 72 will be operated so as to disengage same from the notch 71' and release the plunger 69 to the influence of the spring 71. The end of the lever 74 remote from the arm 65 has pivotally connected thereto a stem 75 which

carries a push button 76 movable through an opening 79 in the front member 50. A spiral spring 80 is disposed in the opening 79 and encircles the stem 75 and constantly tends to hold the stem 75 elevated as will be obvious. By this construction it will be apparent that when a negative is closed in the printing frame B and the hinged back closed the negative will engage the angular portion 70 of the plunger 69 and depress the plunger against the influence of the spring 71. At the termination of this depression of the plunger 69 the sear 72 will engage in the notch 71' and lock the plunger depressed during the printing operation. When it is desired to remove the negative it is only necessary to open the hinged back of the printing frame and then depress the push button 76. This depression of the push button 76 will rock the lever 74 and in turn rock the sear 72 so as to disengage the latter from the notch 71' when the plunger 69 will be elevated under the influence of the spring 71 so as to lift the outer end of the negative to a position where it may be conveniently gripped and removed.

What we claim is:—

1. In a photographic printing apparatus the combination of a casing having a printing frame receiving opening in its top, electrical conductors disposed within said casing, lamps conducting said conductors, means for connecting one end of said conductors with an electrical source, a printing frame seated in the opening in the top of

said casing, a hinged back included in said printing frame, means for connecting the other ends of said conductors operated by the movement of the hinged back to closed position, a slideable plate adapted for movement into engagement with the conductors simultaneously independent of the movement of the hinged back to closed position, spring means normally holding the plate out of engagement with the conductors, and means for moving said plate against the influence of said spring means. 40

2. A photographic printing frame comprising a frame body having a negative supporting ledge along its inner edge, a hinged back secured to said frame body for confining a negative upon said ledge, a plunger slideable in the frame body and having a portion thereof overlying the ledge, spring means constantly tending to elevate 55 said plunger to lift a negative thereabove, a sear for locking said plunger depressed, a push button mounted in the frame body, and connections between said push button and said sear whereby the depression of the former will disengage the latter from the plunger and release same to the influence of said spring means. 60

In testimony whereof, we affix our signatures in the presence of two witnesses.
